VALVE

James W. Whitehurst, Portsmouth, Va.

Application November 15, 1930
Serial No. 495,962

3 Claims. (Cl. 251—82)

This invention relates to valves of the balanced type.

An object of the present invention is to provide a balanced valve of the spool type wherefore in the valve disks may be relatively adjusted exteriorly of the casing and thereafter positively held in adjusted position to compensate for expansion and contraction in the valve parts.

With the above and other objects in view, the invention further includes the following novel features and details of construction, to be hereinafter more fully described, illustrated in the accompanying drawing and pointed out in the appended claims.

15. In the drawing:—

Figure 1 is a sectional view of a valve embodying the invention.

Figure 2 is a bottom plan view.

Figure 3 is an elevation of one of the valve disks with its threaded stem.

Figure 4 is a view partly in elevation and partly in section illustrating the other valve disk and its sleeve or stem.

Referring to the drawing in detail wherein like characters of reference denote corresponding parts, the reference character 10 indicates a valve casing having an intake 11 and an outlet 12 which are adapted for communication with one another through a steam passage or chamber 13 and ports 14 and 15.

The ports 14 and 15 are surrounded by seats 16 and 17 respectively which are adapted to be engaged by disk valves 18 and 19 and these disks are connected so as to operate in synchronism, after the manner of valves of this type.

In order to maintain a proper seating of the disks 18 and 19 so as to prevent leakage, adjustment must be made to compensate for the expansion and contraction of the valve parts, and in order that a maximum of efficiency may be maintained this adjustment must be arranged for convenient operation.

In the present invention, the disk 18 is carried on a threaded stem 20, and threadedly mounted upon this stem is a sleeve 21 which carries the disk 19. The stem 20 extends through the outer end of the sleeve 21 and the latter passes through a stuffing box 22 whose plate 23 is elongated and adjustably held in place by bolts 24.

The outer end of the sleeve 21 is formed with a nut-like wrench engaging portion 25, whereby the sleeve may be conveniently adjusted on the stem so as to obtain an accurate seating for the

disks 18 and 19. The outer end of the wrench engaging portion 25 is provided with a ground face which engages the ground face of a washer 26, and the latter is in turn engaged by the ground face of a lock nut 27 which is mounted upon the stem 20. Thus the parts may be locked against any accidental movement after proper adjustment has been made.

The disk 18 is provided with a guide 28 to maintain the disks in axial alignment with respect to the ports.

Having described the invention what is claimed is:—

1. A balanced valve of the spool type comprising a casing having an inlet and outlet formed with spaced valve seats disposed between said inlet and outlet, a disk mounted for movement toward and away from one of said seats, a second disk normally stationary with respect to the first disk and mounted for movement toward and away from the other of said seats, means for the bodily adjustment of said disks towards and away from each other to effect their spacing in accordance with the spacing of said seats, said means extending to the exterior of the casing for actuation exteriorly thereof, and means operatively connected with one of said disks for simultaneously moving both disks into and out of engagement with their respective seats.

2. A balanced valve of the spool type comprising a casing having an inlet and outlet formed with spaced valve seats disposed between said inlet and outlet, a disk mounted for movement toward and away from one of said seats and provided with a stem extending to the exterior of the casing, a second disk operatively disposed with reference to the other of said seats and having a sleeve disposed in surrounding relation to said stem and extending to the exterior of said casing, means for adjusting said sleeve axially along said stem to definitely space said disks according to the spacing of said valve seats to maintain said disks in corresponding relation to said seats while permitting bodily movement of the same toward and away from said seats, and means constituting an element of the adjusting means and disposed exteriorly of the casing to effect disk adjustment exterior to the casing.

3. A balanced valve of the spool type comprising a casing having an inlet and outlet formed with spaced valve seats disposed between said inlet and outlet, a disk mounted for movement toward and away from one of said seats

and provided with a stem extending to the exterior of the casing, a second disk operatively disposed with reference to the other of said seats and having a sleeve disposed in surrounding relation to said stem and extending to the exterior of said casing, means for adjusting said sleeve axially along said stem to definitely space said disks according to the spacing of said valve seats to maintain said disks in corresponding relation

to said seats while permitting bodily movement of the same toward and away from said seats, said stem being threaded throughout its length and said sleeve being interiorly threaded and having a wrench seat on its exterior end, and a lock nut carried on said stem and movable into and out of binding engagement with the end of said sleeve.
